UNITED STATES PATENT OFFICE.

RUDOLPH H. BECK, OF PHILADELPHIA, PENNSYLVANIA.

DESIGN FOR A CURTAIN-POLE HOLDER.

SPECIFICATION forming part of Design No. 33,375, dated October 16, 1900.

Application filed September 14, 1900. Serial No. 30,073. Term of patent 7 years.

To all whom it may concern:

Be it known that I, RUDOLPH H. BECK, a citizen of the United States, residing at the city of Philadelphia, in the county of Philadelphia and State of Pennsylvania, have invented and produced a new and original Design for Curtain-Pole Holders, of which the following is a specification, reference being had to the accompanying drawings, forming part hereof, in which—

Figure 1 is a side elevational view of a holder, showing my design. Fig. 2 is a similar view, but of the other side of said holder; and Fig. 3 is a top or plan view of Fig. 1.

As illustrated in the drawings, the leading or material feature of my design consists of the configuration or shape of the holder, which, viewed in side elevation, as in Figs. 1 and 2, consists of the flat horizontally-disposed part *a*, arranged sidewise and having at one end a *U*-shaped projection *b*, disposed edgewise

and having one leg depending at right angles to the part *a*. When viewed in top or plan view, as in Fig. 3, the holder presents the appearance of a thin flat strip *a*, disposed edge-wise and having at one end a curved strip *b*, disposed sidewise and terminating in a flat strip *b'*, forming a right-angled continuation of the strip *a*.

Having thus described the nature of my invention, what I claim as new, and desire to secure by Letters Patent, is—

The design for a curtain-pole holder, substantially as illustrated and described.

In testimony whereof I have hereunto set my signature in the presence of two subscribing witnesses.

RUDOLPH H. BECK.
